CONTAINER FOR CAMPHOR BALLS

Filed June 29, 1929

UNITED STATES PATENT OFFICE

SOLOMON JOSEPH, OF MIDDLE VILLAGE, NEW YORK

CONTAINER FOR CAMPHOR BALLS

Application filed June 29, 1929. Serial No. 374,650.

This invention relates to new and useful improvements in camphor ball holders.

The invention has for an object the provision of a device of the class mentioned which is of simple, durable construction, dependable in use and efficient in action, and which may be manufactured and sold at a reasonable cost.

The invention proposes a base plate with arched wire mesh secured thereon forming a container for camphor balls, and end covers slidably engaged on the ends of the base plate and frictionally maintaining their positions and arranged to close the ends of the container, the end plates and base plate being provided with apertures for receiving a support nail from a wall or the like, the base plate to be formed with a partition which may be arranged with an extension plate for increasing its operative height.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:—

Fig. 1 is a plan view of a device constructed according to this invention.

Fig. 2 is a fragmentary side elevational view of Fig. 1.

Fig. 3 is a transverse vertical sectional view taken on the line 3—3 of Fig. 2.

Fig. 4 is a fragmentary plan view looking in the direction of the arrows 4—4 of Fig. 2 but illustrated with the end cover removed.

Fig. 5 is a perspective view of the end cover per se.

Fig. 6 is a vertical sectional view taken on the line 6—6 of Fig. 5.

Fig. 7 is a fragmentary perspective view of a device constructed according to modified form.

Fig. 8 is a transverse sectional view taken on the line 8—8 of Fig. 7.

The reference numeral 10 indicates generally a base plate bent upwards along its longitudinal center forming a partition 11

which is cut off at both ends so as to terminate, as indicated by numerals 12, materially before the ends of the base plate. This base plate is provided with a plurality of apertures 13 providing for the passage of air. Arched wire mesh material 14 is longitudinally arranged upon the base plate and forms a container and maintains its position by reason of having its longitudinal ends clamped by bent up edges 15 from the base plate.

End covers 16 are engaged upon the base plate and close the ends of the container formed by the wire mesh material 14. The end covers 16 each consists of a vertical perforated wall 17 integral at its bottom on a horizontal portion 18 which has lateral bent portions 19 and 20 forming a passage 21. When these end covers are engaged upon the base plate, the ends of the base plate are inserted within the passages 21. The partition 11 is formed by bending a portion of said base plate upon itself and at right angles to the main portion so that the elevated portion consists of adjacent layers which resiliently tend to separate. Friction obtained generally by the spreading action of the layers of the partition is depended upon to maintain the positions of the end covers. Apertures 22 are formed thru the horizontal portion 18 of the end covers and thru the base plate and are intended for providing for the suspension of the device from nails or the like.

In the modified form of the device illustrated in Fig. 7, the partition 11' is formed with a top slot 23. The material from which the partition is formed must be quite springy so that it tends to open providing a spreading force which coacts against the inner sides of the passages 21 for maintaining the positions of the end covers. An extension plate 24 is engaged within the partition 11' and extends thru the slot 23. When the end covers 16 are in place, the arms forming the partition 11' are forced together and frictionally hold the extension plate 24 in a stationary position.

In Figs. 1 to 3, numerals 25 indicate camphor balls. It will be noticed that two rows of these balls are engaged within the device.

The partition 11 serves to separate these two rows. Camphor fumes given off by the balls may radiate thru the mesh 14 and thru the apertures 13. The partition permits the holding of the camphor balls extended from one end to the other end of the device. It is particularly advantageous when economy is desired so that one row of camphor balls may be inserted in the device and the other portion of the container formed by the wire mesh 14 left empty. In the event that smaller camphor balls are used, it is necessary to extend the partition 24 so that the camphor balls from one side of the device may be held from entering the other side.

While I have shown and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:

1. A camphor ball holder, comprising a base plate with a central partition formed by bending the material of the base plate upwards, arched wire mesh secured thereon forming a container, and end covers slidably mounted on the ends of the base plate and covering the ends of the container, said central partition being formed with a slot and a plate extendable thru the slot.

2. A camphor ball holder, comprising a base plate with a central partition formed by bending the material of the base plate upwards, arched wire mesh secured thereon forming a container, and end covers slidably mounted on the ends of the base plate and covering the ends of the container, said central partition being formed with a slot and a plate extendable thru the slot, and frictionally held in various extended positions by the resiliency of the layers forming said partition.

In testimony whereof I have affixed my signature.

SOLOMON JOSEPH.
